MINING APPARATUS

Original Filed July 3, 1924

2 Sheets-Sheet 2

UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed July 3, 1924, Serial No. 723,953. Renewed December 20, 1926.

My invention relates to mining apparatus.

An object of my invention is to provide an

improved mining apparatus. Another ob-

ject of my invention is to provide an im-

proved transport and cutting truck for such

an apparatus. Another object of my inven-

tion is to provide a mining machine trans-

port and cutting truck of an improved con-

struction especially adapted to use in low

10 veins of coal, whereby the machine may be

transported about the mines with facility.

Still another object of my invention is to

provide an improved mining machine trans-

port and cutting truck having improved

15 driving means therefor, whereby the same

may be driven at different speeds directly

from the mining machine feeding mecha-

nism. A still further object of my inven-

20 tion is to provide an improved mining ma-

chine transport and cutting truck having

reversing mechanism thereon, whereby the

truck may be driven in opposite directions

relative to a trackway at fast or slow speeds

25 directly from the mining machine feeding

mechanism. Still another object of my in-

vention is to provide an improved transport

and cutting truck relative to which a mining

machine is adapted to be loaded or unloaded

30 or to which a mining machine may be se-

cured, thereby permitting the mining ma-

chine to cut on the truck or to cut on the

bottom in accordance with the longwall or

the room and pillar methods of cutting, the

truck being driven directly from the mining

35 machine feeding mechanism. These and

other objects and advantages of my inven-

tion will, however, hereinafter more fully

30 appear.

In the accompanying drawings I have

40 shown for purposes of illustration two forms

which my invention may assume in practice.

In these drawings,—

Fig. 1 is a plan view of my improved truck

with a mining machine carried thereon

45 adapted to operate as a mounted cutter, the

drop-front frame being removed and the

cutter bar being shown in a plurality of

positions, the view being partially in section

to facilitate illustration.

50 Fig. 2 is a side elevation, partially in section, of the machine shown in Fig. 1, the

drop-front frame being shown in the plura-

lity of positions thereon.

Fig. 3 is a detail sectional view of a por-

tion of my improved truck driving mecha- 55

nism. Fig. 4 is a detail sectional view through

one of the frictional controlling devices.

Fig. 5 is a side elevation of a modified

60

form of the truck shown in Figs. 1 and 2.

65

In this illustrative form of my invention

shown in Figs. 1 to 4 I have provided a truck

or guiding frame 1 suitably mounted on

wheels 2 secured to axles 3 journaled in the

usual manner in axle boxes 4 and adapted to

move relative to a trackway 5. The forward

end of the truck frame has pivoted thereon

at 6, a detachable drop front loading or un-

loading frame portion 7 provided with an

inwardly projecting operating portion 8 70

which is adapted to be engaged by the bot-

tom of the mining machine during the load-

ing or unloading operation to raise and

lower the same relative to the mine bottom.

The guiding frame 1 is also adapted to re-

ceive a self-propelled, flexibly fed mining

machine, generally designated 9, of the same

general type as that described and claimed

in my copending application Ser. No.

619,839, filed Feb. 19, 1923, the mining ma-

chine being of the longwall type adapted to

slide on its own bottom on the mine bottom

and having an elongated frame 10 which

consists of a feed frame section 11, a motor

frame section 12, and a cutter frame sec-

10

15 tion 13, the frame sections 11, 12 and 13 be-

ing secured together in any suitable man-

ner. Herein, the section 12 contains a uni-

directional pressure fluid actuated driving

motor (not shown) although any suitable

type of air, electric or other motor may be

utilized, if desired. The frame 10 further

15 presents parallel plane surfaces 14 and 15

upon which the machine is selectively adapt-

ed to slide during cutting, that is, when the

195 machine is being used as an undercutter or

an overcutter. The cutting frame section 13

also carries a cutter bar 16 pivoted thereon,

at 17, on a vertical axis and provided with

an endless cutter bit carrying cutter chain 18

which is adapted to be circulated about the

outer edges of the cutter bar in a well known

manner through suitable power connections

(not shown) from the driving motor. The

100 cutter bar 16 is as shown herein also adapted

to be swung or slued about its pivot 17 into

opposite lateral positions relative to the ma-

chine frame and at right angles thereto or

into alinement with the longitudinal axis of the machine frame or into positions intermediate thereof, and as shown herein is also adapted to be locked in these positions by means of a pin 19 adapted to register with suitably located apertures 20 formed in a flanged portion of the cutting frame 13. As illustrated, a detachable swing arm, generally designated 21, may also be inserted in one of the unused apertures 20 thus permitting the machine to be utilized as a room and pillar machine when removed from the truck in a manner described in my copending application Ser. No. 347,571, filed Dec. 15, 1919. A feed operating member or sprocket 22 is also herein suitably journaled on a longitudinally extending horizontal axis on the frame section 11 and adapted to cooperate with a flexible feed chain 23 during the loading and unloading movements of the machine relative to the truck, during cutting, during the swinging operation of the bar, and when the machine is cutting on the bottom as either a longwall or a room and pillar machine or being hauled on the mine bottom at a fast or haulage speed. The feed sprocket 22 is herein, as in my prior application Ser. No. 619,839, adapted to be driven at a slow speed through one train of mechanism (not shown) under the control of a frictional controlling device of the disc clutch type, generally designated 24 (see Fig. 4) and through another train (not shown) at a fast speed in the opposite direction under the control of a similar frictional controlling device, generally designated 25, these controlling devices 24 and 25 forming a part of the feeding mechanism of the machine per se and being adapted to be alternatively operated as described in my copending application Ser. No. 619,839 by means of a controlling member or hand wheel 26 disposed at the rear end of the frame section 11.

In my improved construction it will be observed that an annular member 27 is suitably secured to and rotatable with the feed sprocket driving shaft 28 by means of a suitable bolt connection 29, and that this member 27 is provided with internal clutch teeth 30 adapted to cooperate with external clutch teeth 31 formed on a longitudinally extending horizontal shaft 32 suitably journaled in bearings 33 in a frame or casing member 34 suitably secured to the rear end of the truck frame 1. The rearward end of the shaft 32 is provided with a bevel pinion 35 which is adapted to mesh constantly with bevel gears 36 and 37 loosely journaled on a transverse horizontal truck driving shaft 38, the gears 36 and 37 being adapted to be alternatively connected to the shaft 38 by means of a jaw clutch 39 provided with shipper mechanism 40 and a suitable operating handle 41 disposed at the top of the casing

34. The shaft 38 is suitably journaled in bearings 42 and 43 suitably carried by the truck frame and the gear casing 34, respectively, and has secured thereto at one end a spur gear 44 adapted to mesh with a spur gear 45 suitably secured to a transverse horizontal shaft 46 disposed parallel with and below the shaft 38 and to which a sprocket 47 is suitably secured which is adapted to drive the truck wheels 2 by means of chain and sprocket connections 48 and 49 disposed within the outer limits of the truck frame. The shaft 38 is provided with a suitable frictional braking device 50 provided with a suitable operating handle 51 which is adapted to be applied to retard the rotation of the shaft 38, for instance, when the truck is moving relative to a trackway of a steep gradient.

In the use of my improved mining apparatus it will be observed that the truck may be driven relative to the trackway at a fast or at a slow speed in opposite directions directly from the mining machine feeding mechanism under the control of the mining machine feed control frictional devices 24 and 25, and may also be driven in the reverse of these directions by means of the reverse gears 36 and 37 and the controlling clutch 39 carried on the truck, any desired variants of these speeds of course also being obtainable. The truck may be controlled in either of these directions by means of the braking device 50. It will also be noted that the mining machine may be removed from the truck by using the flexible feeding member in a usual manner, the teeth 31 on the shaft 32 separating at this time from the teeth 30 formed on the member 27 carried by the feed sprocket 22 and the drop front 7 automatically lowering to the mine bottom as the center of gravity of the machine passes over the operating portion 8. The machine may then operate as a longwall machine or, if desired, the swing arm 21 may be inserted in one of the apertures 20, thereby permitting the machine to operate as a room and pillar machine in the usual manner. Furthermore it will be noted that the machine may be rigidly bolted to the truck as by screws 52, the drop front frame then being removed, and the cutter bar swung to the dotted position indicated by A in Fig. 1 and locked in that position by means of the locking pin permitting the machine and its truck to advance under the propulsion of the truck wheels and the control of the friction 24 to effect cutting at the desired slow or cutting speed of approximately three feet per minute while making its sumping cut. The bar is then slewed or swung by the flexible feeding member to its opposite angular position, as indicated by dotted lines by B in Fig. 1, and the truck retracted from the face, in a like manner, this being ef-

fected by simply throwing the clutch 39 to reverse the truck wheel drive and this operation likewise being under the control of a mining machine feed controlling mechanism.

5 During transport from one place to another the mounted cutter will obviously be driven through the fast feed friction 25 at the desired transport speed of approximately 100 feet per minute. It will also be noted that the 10 machine may slide selectively on the plane surfaces 14 and 15 on the mine bottom or on the truck, consequently varying the plane of the cutter bar relative to the mine bottom or to the truck when cutting on the latter.

15 In the form of my invention shown in Fig. 5 it will be observed that a truck body 55 is mounted on wheels 56 movable relative to the trackway 5, this truck body carrying an adjustable frame 57 on which is carried 20 the complete mining machine 9 and the truck driving mechanism including the shaft 38, which is substantially the same as that shown in Figs. 1 and 2. As shown, the mining machine 9 drives the truck wheels from 25 the shaft 38 under the control of the frictional devices 24 and 25 hereinbefore described through a chain and sprocket connection 58 to an intermediate transverse horizontal shaft 59 journaled on the frame 57 and the chain and sprocket connections 60 and 61. A plurality of lifting jack mechanisms, generally designated 62, which are 30 of a type substantially similar to those described in my copending application Ser. No. 35 508,390, filed October 17, 1921, now Patent No. 1,648,879, granted Nov. 8, 1927, are provided between the truck 55 and the adjustable frame 57. Each of these jack mechanisms comprises a threaded screw member 63 pivoted to the frame 57 by a universal connection 64 and which member telescopes into a larger threaded screw member 65 provided with a ratchet and pawl manual operating mechanism 66. The member 65 is, in turn, 40 threaded into a casing 67 pivoted at 68 on a transverse horizontal axis on a bracket 69 carried by the truck body 55. In order to maintain the shaft 59 in a fixed spaced relation with respect to the rear axle of the truck, I have provided a spacing member 50 70 which comprises elements 71 and 72 pivoted together at 73, the latter element also being pivoted at 74 on the front axle 75 of the truck, while the member 71 is pivoted 55 at 76 to the adjustable frame 57. By this mechanism it will be observed that as the jack mechanisms 62 are operated the frame 57 is caused to move upwardly in an arcuate path about an axis in a predetermined 60 fixed relationship with respect to the front axle 75, at the same time through the pivotal connection 73 between elements 71 and 72, the lateral adjustment of the frame is permitted. Furthermore, attention is directed to 65 the fact that by making connection between

the front axle and the shaft 76 it is possible to maintain the truck driving shaft 38 and the shaft 59 in operative driving relation to the truck wheels in any vertically adjusted position of the frame 57, thereby permitting the truck to be propelled relative to the trackway directly from the mining machine feeding mechanism including the frictional controlling members 24 and 25 at a slow cutting speed or at a fast haulage speed. The 70 operation of the mining machine in this form of my invention is substantially the same as that brought out in regard to Figs. 1 and 4, and further description is therefore 75 deemed unnecessary.

80 While I have in this application specifically described two forms which my invention may assume in practice, it will be understood that these forms of the same are shown for purposes of illustration and that the invention may be modified and embodied in various other forms without departing from its spirit or the scope of the appended claims.

85 What I claim as new and desire to secure by Letters Patent is:

90 1. In a mining apparatus, a wheeled truck, a unitary, separably operable mining machine thereon operable to cut in different planes when supported in inverted positions, and means to propel said truck therefrom when disposed in either position.

95 2. In a mining apparatus, a wheeled truck, a unitary, separably operable mining machine thereon operable to cut in different planes when supported in inverted positions, and means to propel said truck therefrom at either a cutting speed or a transport speed when disposed in either position.

100 3. In a mining apparatus, a wheeled truck, a unitary, separably operable mining machine thereon operable to cut in different planes when supported in inverted positions, and means to propel said truck therefrom at either a cutting speed or a transport speed in opposite directions when disposed in either position.

105 4. In a mining apparatus, a wheeled truck, a unitary, separably operable mining machine thereon operable to cut in different planes when supported in inverted positions, and means to propel said truck from said mining machine at different speeds and in opposite directions when disposed in either position.

110 5. In a mining apparatus, a wheeled truck, a unitary, separably operable mining machine thereon operable to cut in different planes when supported in inverted positions, means for propelling said truck from said mining machine at different speeds in opposite directions when disposed in either position, and means to reverse said truck at any speed.

115 6. In a mining apparatus, a wheeled truck, a mining machine thereon operable to cut in

- different planes when supported in inverted positions and provided with a feed operating member adapted to cooperate directly with flexible feeding means, and means to 5 propel said truck from said feed operating member at a plurality of speeds in opposite directions in different positions of said machine.
7. In a mining apparatus, a wheeled truck, 10 a unitary, separably operable mining machine thereon operable to cut in different planes when supported in inverted positions and provided with a feed operating member adapted to cooperate directly with flexible 15 feeding means, and means to propel said truck from said feed operating member at a plurality of speeds in opposite directions in different positions of said machine, and means to reverse said truck at any speed.
- 20 8. In a mining apparatus, a wheeled truck, a mining machine thereon provided with a feed operating member disposed on a longitudinally extending horizontal axis and adapted to cooperate directly with flexible 25 feeding means, and means adapted to be clutched to said member to propel said truck from said mining machine at a plurality of speeds in opposite directions including reversing mechanism on said truck.
- 30 9. In a mining apparatus, a wheeled truck, a mining machine thereon provided with a feed operating member adapted to cooperate directly with flexible feeding means, means to propel said truck at a plurality of speeds 35 from said feed operating member, and reversing mechanism for said truck carried on the latter and including a clutch disposed between said feed operating member and said truck wheels.
- 40 10. In a mining apparatus, a wheeled truck, a unitary, separably operable mining machine thereon including means to propel said truck at different speeds and means to vary said speeds, and reversing mechanism 45 for said truck on the latter including a clutch, bevel gearing, and a transverse shaft operatively connected to the wheels.
- 50 11. In a mining apparatus, a wheeled truck, a unitary, separably operable mining machine thereon including means to propel said truck at different speeds and means to vary said speeds, reversing mechanism for said truck on the latter including a transverse shaft journaled thereon and operatively connected to the wheels, and means to 55 brake the rotation of said shaft.
- 60 12. In a mining apparatus, a wheeled truck having a frame adjustable thereon into different horizontal planes, a unitary, separably operable mining machine carried on said adjustable frame including a feed operating mechanism providing a cutting speed and a transport speed, transmission means disposed between said feed operating mechanism and the wheels of said truck operative 65

to feed the latter at either cutting speed or transport speed, and means to maintain said transmission means operative irrespective of the adjusted position of said machine carrying frame.

70 13. In a mining apparatus, a wheeled truck having a frame adjustable thereon into different horizontal planes, a unitary, separably operable mining machine carried on said adjustable frame including a feed operating member and means for rotating the latter at a cutting speed or a transport speed, transmission means disposed between said feed operating member and the wheels of said truck operative to feed the latter at either cutting speed or transport speed, and means to maintain said transmission means operative irrespective of the adjusted position of said machine carrying frame.

75 14. In a mining machine, a wheeled truck having a frame adjustable thereon into different horizontal planes, a unitary, separably operable mining machine carried on said adjustable frame including feed operating mechanism operable at a different speed in opposite directions, transmission means disposed between said feed operating mechanism and the wheels of said truck, and means to maintain said transmission operative irrespective of the adjusted position 80 of said machine carrying frame.

85 15. In a mining apparatus, a wheeled truck having a frame adjustable thereon into different horizontal planes, a unitary, separably operable mining machine carried on said adjustable frame operable to cut in different planes when supported in inverted positions including a feed operating member and means for rotating the latter at a cutting speed or a transport speed, transmission means disposed between said feed operating member and the wheels of said truck operative to feed the latter at either cutting speed or transport speed, and means to 90 maintain said transmission means operative irrespective of the adjusted position of said machine carrying frame.

95 16. In a mining apparatus, a wheeled truck having a frame adjustable thereon into different horizontal planes, a unitary, separably operable mining machine carried on said adjustable frame operable to cut in different planes when supported in inverted positions including a feed operating member disposed in the vertical center of said machine and means for rotating the latter at a cutting speed or a transport speed, transmission means disposed between said feed operating member and the wheels of said truck operative to feed the latter at either cutting speed or transport speed, and means to 100 maintain said transmission means operative irrespective of the adjusted position of said machine carrying frame.

105 17. In a mining apparatus, a wheeled truck having a frame adjustable thereon into different horizontal planes, a unitary, separably operable mining machine carried on said adjustable frame operable to cut in different planes when supported in inverted positions including a feed operating member disposed in the vertical center of said machine and means for rotating the latter at a cutting speed or a transport speed, transmission means disposed between said feed operating member and the wheels of said truck operative to feed the latter at either cutting speed or transport speed, and means to 110 maintain said transmission means operative irrespective of the adjusted position of said machine carrying frame.

115 18. In a mining apparatus, a wheeled truck having a frame adjustable thereon into different horizontal planes, a unitary, separably operable mining machine carried on said adjustable frame operable to cut in different planes when supported in inverted positions including a feed operating member disposed in the vertical center of said machine and means for rotating the latter at a cutting speed or a transport speed, transmission means disposed between said feed operating member and the wheels of said truck operative to feed the latter at either cutting speed or transport speed, and means to 120 maintain said transmission means operative irrespective of the adjusted position of said machine carrying frame.

125 19. In a mining apparatus, a wheeled truck having a frame adjustable thereon into different horizontal planes, a unitary, separably operable mining machine carried on said adjustable frame operable to cut in different planes when supported in inverted positions including a feed operating member disposed in the vertical center of said machine and means for rotating the latter at a cutting speed or a transport speed, transmission means disposed between said feed operating member and the wheels of said truck operative to feed the latter at either cutting speed or transport speed, and means to 130 maintain said transmission means operative irrespective of the adjusted position of said machine carrying frame.

truck having a frame adjustable thereon into different horizontal planes, a mining machine carried on said adjustable frame operable to cut in different planes when supported in inverted positions including a feed operating member disposed in the vertical and longitudinal center of said machine and means for rotating the latter at a cutting speed or a transport speed, transmission means disposed between said feed operating member and the wheels of said truck operative to feed the latter at either cutting speed or transport speed, and means to maintain said transmission means operative irrespective of the position of said mining machine.

18. In a mining apparatus, a wheeled truck having a frame adjustable thereon into different horizontal planes, a mining machine carried on said adjustable frame including a feed operating member operable at different speeds in opposite directions and friction controlling means for each speed, transmission means disposed between said feed operating member and the wheels of said truck, and means to maintain said transmission means operative irrespective of the adjusted position of said mining machine.

19. In a mining apparatus, a wheeled truck, a unitary mining machine of the separably operable type thereon having a frame providing a plurality of surfaces upon each of which the machine may rest and operable to cut in different planes when supported in different positions on said surfaces, and means to propel said truck therefrom when disposed in such different positions.

20. In a mining apparatus, a wheeled truck, a mining machine comprising cutting mechanism and a frame providing a plurality of plane surfaces upon each of which said machine may rest during cutting and so related to said cutting mechanism that the latter occupies different planes when said machine is resting on said different surfaces, and means on said machine and truck cooperating when said machine rests upon any of said surfaces upon said truck to effect truck propulsion.

21. In a mining apparatus, a wheeled truck having a machine supporting surface, a unitary mining machine of the separably operable type comprising cutting mechanism and a frame providing a plurality of surfaces upon each of which said machine may rest during cutting and so related to said cutting mechanism that the latter occupies different planes when said machine is resting on said different surfaces, and means on said machine and truck cooperating when said machine rests upon any of its said surfaces upon the machine supporting surface of said truck to effect truck propulsion.

22. In a mining apparatus, a wheeled

truck, a mining machine comprising cutting mechanism and a frame providing a plurality of surfaces upon each of which said machine may rest during cutting and so related to said cutting mechanism that the latter occupies different planes when said machine is resting on said different surfaces, and means on said machine and truck cooperating when said machine rests upon any of said surfaces upon said truck to effect truck propulsion including a power transmitting element on said machine constituting the terminal truck driving element thereon equidistant from each of said surfaces upon said machine.

23. In a mining apparatus, a wheeled truck, a mining machine comprising cutting mechanism and a frame providing a plurality of surfaces upon each of which said machine may rest during cutting and so related to said cutting mechanism that the latter occupies different planes when said machine is resting on said different surfaces, and means on said machine and truck cooperating when said machine rests upon any of said surfaces upon said truck to effect truck propulsion including power transmission means on said machine constituting the terminal truck driving means thereon equidistant from each of said surfaces upon said machine.

24. In a mining apparatus, a wheeled truck, a mining machine thereon operable to cut in different planes when supported in different positions and provided with a feed operating member adapted to cooperate directly with flexible feeding means, and means to propel said truck from said feed operating member at a plurality of speeds in opposite directions in different positions of said machine.

25. In a mining apparatus, a wheeled truck, a unitary mining machine of the separably operable type thereon operable to cut in different planes when supported in different positions and provided with a feed operating member, means to propel said truck from said feed operating member at a plurality of speeds in opposite directions in different positions of said machine, and means to reverse said truck at any speed.

26. In a mining apparatus, a wheeled truck, a mining machine thereon provided with a feed operating member adapted to cooperate directly with flexible feeding means and disposed on an axis extending longitudinally of the mining machine, a coaxial driving shaft therefor, and means rotatable by said shaft for propelling said truck from said mining machine in opposite directions including reversing mechanism on said truck.

27. In a mining apparatus, a wheeled truck, a mining machine thereon provided with a feed operating member adapted to

cooperate directly with flexible feeding means and disposed on an axis extending longitudinally of the mining machine, a coaxial driving shaft therefor, and means rotatable by said shaft for propelling said truck from said mining machine in opposite directions at a plurality of speeds including reversing mechanism on said truck.

28. In a mining apparatus, a wheeled truck, a unitary mining machine of the separably operable type thereon having pivoted cutting mechanism and a shaft extending longitudinally of said machine, reversing mechanism on said truck driven directly by said shaft and operatively connected in driving relation with the truck wheels, and means for swinging said cutting mechanism including an element rotatable with said shaft.

29. In a mining apparatus, a wheeled truck, a mining machine thereon having pivoted cutting mechanism and a shaft extending longitudinally of said machine, reversing mechanism on said truck driven directly by said shaft and operatively connected in driving relation with the truck wheels, and means for swinging said cutting mechanism including an element rotatable with said shaft and flexible connections between the same and said cutting mechanism.

30. In a mining apparatus, a wheeled truck, a unitary mining machine of the separably operable type thereon having cutting mechanism mounted to permit adjustment thereof and a shaft extending longitudinally of said machine, reversing mechanism on said truck driven directly by said shaft and operatively connected in driving relation with the truck wheels, and means for adjusting said cutting mechanism including an element rotatable with said shaft.

31. In a mining apparatus, a wheeled truck, a mining machine thereon having cutting mechanism mounted to permit adjustment thereof and a shaft extending longitudinally of said machine, reversing mechanism on said truck driven directly by said shaft and operatively connected in driving relation with the truck wheels, and means for adjusting said cutting mechanism including an element rotatable with said shaft and flexible connections between the same and said cutting mechanism.

32. In a mining apparatus, a wheeled truck, a unitary mining machine of the separably operable type thereon having pivoted cutting mechanism and a shaft extending longitudinally of said machine, reversing mechanism on said truck driven directly by said shaft and operatively connected in driving relation with the truck wheels, and means for swinging said cutting mechanism including an element rotatable with said shaft and nearer to the cutting mechanism than is said reversing mechanism.

33. In a mining apparatus, a wheeled truck, a mining machine thereon having pivoted cutting mechanism and a shaft extending longitudinally of said machine, reversing mechanism on said truck driven directly by said shaft and operatively connected in driving relation with the truck wheels, and means for swinging said cutting mechanism including an element rotatable with said shaft and nearer to the cutting mechanism than is said reversing mechanism and flexible connections between the same and said cutting mechanism.

34. In a mining apparatus, a wheeled truck, a unitary mining machine of the separably operable type thereon having cutting mechanism mounted to permit adjustment thereof and a shaft extending longitudinally of said machine, reversing mechanism on said truck driven directly by said shaft and operatively connected in driving relation with the truck wheels, and means for adjusting said cutting mechanism including an element rotatable with said shaft and nearer to the cutting mechanism than is said reversing mechanism.

35. In a mining apparatus, a wheeled truck, a mining machine thereon having cutting mechanism mounted to permit adjustment thereof and a shaft extending longitudinally of said machine, reversing mechanism on said truck driven directly by said shaft and operatively connected in driving relation with the truck wheels, and means for adjusting said cutting mechanism including an element rotatable with said shaft and nearer to the cutting mechanism than is said reversing mechanism and flexible connections between the same and said cutting mechanism.

36. In a mining apparatus, a wheeled truck, a mining machine thereon having a feed operating member rotatable on an axis extending longitudinally of the machine and adapted to cooperate with flexible feeding means, and mechanism for propelling said truck comprising an element connectable directly to said feed operating member for rotation therewith.

37. In a mining apparatus, a wheeled truck, a mining machine thereon having a feed operating member rotatable on an axis extending longitudinally of the machine and adapted to cooperate with flexible feeding means, and mechanism for propelling said truck in opposite directions comprising reversing mechanism, and an element connectable directly to said feed operating member for rotation therewith.

38. In a mining apparatus, a wheeled truck, a mining machine thereon having a feed operating member rotatable on an axis extending longitudinally of the machine and adapted to cooperate with flexible feeding means, and mechanism for propelling said

truck at either a cutting speed or a transport speed comprising an element connectible directly to said feed operating member for rotation therewith.

5 39. In a mining apparatus, a wheeled truck, a mining machine thereon having a feed operating member rotatable on an axis extending longitudinally of the machine and adapted to cooperate with flexible feeding

10 means, and mechanism for propelling said truck at either a cutting speed or a transport speed in opposite directions comprising an element connectible directly to said feed operating member for rotation therewith.

15 40. In a mining apparatus, a wheeled truck, a mining machine thereon having a feed operating member rotatable on an axis extending longitudinally of the machine and adapted to cooperate with flexible feeding 20 means, said feed operating member being rotatable in opposite directions, and mechanism for propelling said truck in opposite directions comprising an element connectible directly to said feed operating member for 25 rotation therewith.

41. In a mining apparatus, a wheeled truck, a mining machine thereon having a feed operating member rotatable on an axis extending longitudinally of the machine and 30 adapted to cooperate with flexible feeding means, said feed operating member being rotatable in opposite directions at either a cutting speed or at a higher speed, and mechanism for propelling said truck in opposite 35 directions at different speeds comprising an element connectible directly to said feed operating member for rotation therewith.

42. In a mining apparatus, a wheeled truck, a mining machine thereon having a feed operating member rotatable on an axis 40 extending longitudinally of the machine and adapted to cooperate with flexible feeding means, said feed operating member being rotatable at a plurality of speeds in opposite directions, and mechanism for propelling said truck at different speeds comprising an element connectible directly to said feed operating member for rotation therewith, and means on said truck to reverse the 45 same at any speed.

43. In a mining apparatus, a truck frame having running gear, a mining machine having opposed plane surfaces upon which it is disposable and constructed to cut when sliding directly upon the mine bottom on either 50 of such surfaces, and means to connect such machine in driving relation to said running gear when said machine is disposed in either position on said frame.

60 44. In a mining apparatus, a truck frame having running gear and propulsion mechanism therefor, a mining machine mounted thereon, said machine being of the type adapted to slide on the mine bottom during

cutting and having a plurality of surfaces 65 each adapted to support the machine, and means for operatively connecting said propulsion mechanism with said machine when the latter is disposed on any of said surfaces on said truck frame including a member on 70 said machine occupying approximately the same position relative to said frame in the several dispositions of the machine thereon.

45. Mining apparatus comprising a wheeled truck, and a unitary mining machine of the separately operable, swinging cutter bar type carried on said truck and disposable thereon in different positions in which said bar is swingable in different planes, said machine and truck having co-operating parts adapted to effect truck propulsion including a driving member on said machine and a driven member on said truck, said driving member being so disposed on said machine that the position of 80 its axis of rotation is the same with said machine disposed for bar swing in different planes.

46. Mining apparatus comprising a wheeled truck and a unitary mining machine of the separately operable type comprising cutting mechanism and carried on said truck and disposable relative thereto in different positions in which said cutting mechanism lies in different planes, said machine and truck having cooperating parts adapted to effect truck propulsion and including a driving member on said machine and a driven member on said truck, said driving member being so disposed on said 90 machine that the position of its axis of rotation is the same with said machine disposed to locate said cutting mechanism in 95 different planes.

47. Mining apparatus comprising a wheeled truck and a unitary mining machine of the separately operable, swinging cutter bar type arranged to cut in different planes when supported in inverted positions on said truck, said machine being provided 100 with a driving member whose axis of rotation is disposed in the intersection of the central longitudinal vertical plane and the central longitudinal horizontal plane of the machine and said truck having a driven 105 member engageable with said driving member to effect propulsion of said truck when the machine is disposed on the latter in either of its inverted positions.

48. Mining apparatus comprising a wheeled truck and a unitary mining machine of the separately operable, swinging cutter bar type arranged to cut in different planes when supported in inverted positions on the truck, said truck being provided with a member adapted to be driven from said machine and to constitute a driving member for the truck wheels and said 120 125

- machine being provided with driving means adapted to cooperate with said driven member and disposed midway between the sides of the machine.
49. Mining apparatus comprising a wheeled truck and a unitary mining machine of the separately operable, swinging cutter bar type arranged to cut in different planes when supported in inverted positions on the truck, said truck being provided with a member adapted to be driven from said machine and to constitute a driving member for the truck wheels and said machine being provided with driving means adapted to cooperate with said driven member and disposed midway between the top and bottom surfaces of the machine.
50. Mining apparatus comprising a wheeled truck and a unitary mining machine of the separately operable, swinging cutter bar type arranged to cut in different planes when supported in inverted positions on the truck, said machine being provided with a driving member rotating on an axis in the central longitudinal vertical plane of the machine and said truck being provided with means positioned for driving by
- said driving member in either inverted position of said machine.
51. Mining apparatus comprising a 30 wheeled truck and a unitary mining machine of the separately operable, swinging cutter bar type arranged to cut in different planes when supported in inverted positions on the truck, said machine being provided 35 with a driving member rotating on an axis in the central longitudinal horizontal plane of the machine and said truck being provided with means positioned for driving by said driving member in either inverted 40 position of said machine.
52. In a mining apparatus, a truck frame having running gear, a unitary, separately operable, mining machine having different 45 surfaces on which it may be supported during operation and operable to cut in different planes when supported on said different surfaces, and means to connect said machine in driving relation to said running gear when said machine is disposed on any 50 of such surfaces on said frame.

In testimony whereof I affix my signature.

MORRIS P. HOLMES.
